[57] **CLAIM**

The ornamental design for a fishing lure, as shown and described.

DESCRIPTION

FIG. 1 is a top plan view of the fishing lure showing my new design;

FIG. 2 is a ring end view thereof;

FIG. 3 is a hook end view thereof;

FIG. 4 is a side view thereof;

FIG. 5 is a bottom plan view thereof;

FIG. 6 is an opposite side view thereof;

FIG. 7 is a cross-sectional view thereof taken along the line 7—7 in FIG. 1;

FIG. 8 is a cross-sectional view thereof taken along the line 8—8 in FIG. 1;

FIG. 9 is a top perspective view thereof;

FIG. 10 is a top perspective view of a fishing lure showing a second embodiment of my new design the sole difference being in the surface texture; and,

FIG. 11 is a top plan view of FIG. 10.

The broken line showing of the ring and hook in the Figures is for illustrative purposes only and forms no part of the claimed design.
